United States Patent Office.

GEORGE PUSTKUCHEN, OF NEW YORK, N. Y.

Design No. 4,042, dated May 17, 1870.

DESIGN FOR A PACKAGE.

The Schedule referred to in these Letters Patent and making part of the same.

To all whom it may concern:

Be it known that I, **GEORGE PUSTKUCHEN**, of the city, county, and State of New York, have invented a new and original Design for Package; and I do hereby declare that the following is a full, clear, and exact description thereof, which will enable others skilled in the art to make and use the same, reference being had to the accompanying drawing forming part of this specification, in which—

Figure 1 represents a perspective view of my new design for a package, and

Figure 2, an end view of the same.

This invention relates to a new design for a package made of pasteboard or other suitable material, and consists in making such package of prismatic form with pyramidal ends, as is clearly illustrated in the drawing.

I claim as my invention—

The design for a package, as shown.

G. PUSTKUCHEN.
